UNITED STATES PATENT OFFICE.

HOMER S. ROGERS, OF MILWAUKEE, WISCONSIN, ASSIGNOR TO JOHN R. BALL, OF MILWAUKEE, WISCONSIN.

PNEUMATIC PUMP.

1,339,224.

Specification of Letters Patent.

Patented May 4, 1920.

Application filed June 14, 1918. Serial No. 240,008.

To all whom it may concern:

Be it known that I, HOMER S. ROGERS, a citizen of the United States, residing at Milwaukee, in the county of Milwaukee and 5 State of Wisconsin, have invented certain new and useful Improvements in Pneumatic Pumps, of which the following is a specification, reference being had to the accompanying drawing, forming a part thereof.

10 This invention relates to pneumatic pumps and the object of the invention is to improve the construction of pneumatic pumps in the manner to be hereinafter described and claimed.

15 The drawing which accompanies this specification and which forms a part hereof illustrates a vertical section of a pneumatic pump embodying in its construction this invention.

20 Referring to the drawing, the reference numeral 1 designates a main pump chamber, 2 a supplementary pump chamber, 3 a water delivery pipe, 4 and 5 water inlet valves, 6 and 7 water outlet valves, and 8 a pipe for conducting compressed air to the pump chambers. The reference numeral 9 designates an exhaust chamber which can be placed in communication with the main pump chamber 1 and the supplementary 25 chamber 2 through the exhaust ports 10 and 11 whenever the exhaust valves 12 and 13 are open or off their seats. An exhaust pipe 14 may extend from the exhaust chamber 9 to a point above the surface of 30 the water in which the pump may be submerged. The exhaust ports 10 and 11 are made large enough so that the exhaust valves 12 and 13 will be maintained on their seats, when seated, by the difference between the pressures on their opposite sides. 35 The exhaust valve 12, the air valve 15 and a float 16 are connected to a lever 17 which is pivoted in the main pump chamber 1. When the main pump chamber 1 is filling 40 with water, the float 16 will rock the lever 17 and raise the exhaust valve 12 toward its seat and open the air valve 15. The rush of the compressed air in attempting to escape through the exhaust port 10 and the 45 pressure of the compressed air on the lower side of the exhaust valve 12 will seat or close the exhaust valve and it will be kept seated or closed, until forced from its seat, by the difference between the pressures on 50 opposite sides thereof. By properly pro-

portioning the size or area of the exhaust port 10, the exhaust valve 12 will be kept seated even when the water level in the main pump chamber 1 has fallen below the 60 float 16. A pipe 18 extends down below the low water level in the main pump chamber 1 so that its lower end is always water sealed and a valve 19 can prevent water passing up through pipe 18 when a float 20 lifts the valve to prevent communication between 65 the pump chamber and the pipe. The pipe 18 communicates with a fluid motor 21 which is illustrated as provided with a movable part or diaphragm 22. A bleed hole 23 may be provided to permit the escape of 70 air which may separate from the water and a plunger head 24 is pressed against the diaphragm 22 by a spring 25. The spring 25 should not be strong enough to resist the pressure against the diaphragm 22, 75 when the diaphragm is acted on by water under a pressure produced by the pressure of the compressed air in the main pump chamber 1, but may be strong enough to overcome the buoyancy of the float 20 and 80 open valve 19 to force water out of the fluid motor 21. The exhaust valve 12 is provided with a stem 26 and a bell-crank lever 27 pivoted to the plunger head 24 and to the pump case can press upon the stem 85 26 and force the exhaust valve 12 from its seat whenever the valve 19 is opened by the lowering of the water level in the main pump chamber 1. It will be understood, of course, that the area of the diaphragm 22 is 90 greater than the area of the exhaust port 10 to enable the exhaust valve 12 to be forced from its seat.

95 A second fluid motor 28 is provided with a movable part or diaphragm 29 and is in open communication with the lower part of the main pump chamber 1 through a passageway 30 and a pipe 31. The exhaust valve 13 and the air valve 32 for the supplementary pump chamber 2 are connected 100 with a pivoted lever 33 and can be moved positively in either direction by a plunger head 34 which can be moved in one direction by the diaphragm 29. A lever 35 is pivotally connected with the pump case and 105 is also pivotally connected with the plunger head 34 and with a rod 36 which lies in the path of movement of the plunger head 24. The diaphragm 29 is of less size or area than the diaphragm 22 so that, al-

though the same pressure per square inch is exerted on both diaphragms, the total pressure against diaphragm 22 is greater and diaphragm 22 will bulge out and force diaphragm 29 back thereby forcing water out of the second fluid motor 28 back into the main pump chamber 1.

The operation of the pump will be readily understood from an inspection of the drawing. The parts are shown in the positions which they occupy after the main pump chamber 1 has filled with water to the point where the float 16 has rocked the lever 17 and opened the air valve 15 and the exhaust valve 12 has been seated. The compressed air is entering the main pump chamber 1 and is forcing the water therein out through the water delivery pipe 3. The water inlet valve 4 is closed and the water outlet valve 6 is open and water has been forced into the second fluid motor 28 and has forced the diaphragm 29, plunger head 34, lever 35 and rod 36 to the right and opened the exhaust valve 13 and closed the air valve 32. The supplementary pump chamber 2 is filling with water, the water inlet valve 5 being open and the water outlet valve 7 being closed.

As the water level falls or lowers in the main pump chamber 1, the exhaust valve 12 will be kept closed or maintained on its seat by the difference between the pressures on opposite sides thereof and the float 20 will fall with the water, when the water level reaches the line of flotation of the float, until the float is supported by the valve 19. The valve 19 is subjected to a greater pressure in the main pump chamber 1 than the pressure in pipe 18 so that the valve 19 will be kept closed by the difference between the pressures on opposite sides thereof until the water level in the main pump chamber 1 has been lowered enough below the line of flotation of the float 20 so that the weight of the float will open the valve. As soon as the valve 19 has been moved from its seat the pressures on opposite sides thereof will be equalized and the weight of the float 20 will pop it open suddenly. Water will be forced into the fluid motor 21 and will bulge the diaphragm 22 out and force the plunger head 24 to the left. The plunger head 24 will rock the bell-crank lever 27 and force the exhaust valve 12 from its seat. As soon as the exhaust valve 12 is forced from its seat the pressures on the opposite sides thereof will be equalized and the valve will fall and close the air valve 15. The compressed air will exhaust from the main pump chamber 1, the water outlet valve 6 will close and the water inlet valve 4 will open and the pump chamber 1 will fill with water. The spring 25 will return the plunger head 24 to the position shown by the drawing, the water

exhausting from the fluid motor 21 into the main pump chamber 1. When the plunger head 24 was forced to the left, it contacted with the rod 36 and forced the rod 36 to the left thereby forcing water out of the second fluid motor 28 into the main pump chamber 1 and closing the exhaust valve 13 and opening the air valve 32. When the compressed air was admitted to the supplementary pump chamber 2, the water inlet valve 5 closed and the water outlet valve 7 opened and water was forced out through the water delivery pipe 3. When the plunger head 24 is pushed to the right by the spring 25, the rod 36 does not move to the right because there is not enough pressure against the diaphragm 29 to force the exhaust valve 13 from its seat against the pressure of the air in the supplementary pump chamber 2, so water is being discharged from the supplementary pump chamber 2 while the main pump chamber 1 is filling with water. As the action of the valve mechanism in the pump chamber 1 is solely dependent upon the water levels therein and as the discharge of water from the supplementary chamber 2 is timed and initiated by the operation of the mechanism for permitting the main pump chamber 1 to fill with water, to prevent any possibility of compressed air escaping from the supplementary pump chamber 2 through the water delivery pipe 3 and thereby wasting compressed air, a float valve 37 may be confined by a cage 38 so as to close the outlet 39 from the supplementary pump chamber 2 when the water level has been lowered sufficiently.

When the water is entering and filling the main pump chamber 1 the water inlet valve 4 is open and the water outlet valve 6 is closed. As the water level rises, the float 20 is raised and closes the valve 19. As the water level rises farther, the float 16 is raised and swings the lever 17 to close the exhaust valve 12 and open the air valve 15. In the construction illustrated by the drawing, the air valve 15 acts as a stop to limit the movement of the exhaust valve 12 away from its seat and the total movement of the exhaust valve 12 is small so that, while the air valve 15 is opened as the exhaust valve 12 is being closed, the exhaust valve 12 is so close to its seat when the compressed air is admitted to the main pump chamber 1 that the compressed air seats the exhaust valve 12 by the difference between the pressures on opposite sides thereof. This seating of the exhaust valve 12 is also aided by the compressed air attempting to rush by it and by the greater surface of the air valve 15 which is exposed to the rush of the compressed air when the air valve 15 is open.

It will be readily seen that the main pump chamber 1 is emptied and filled as though

the pump were a single chamber pump and that a continuous flow of water is obtained by a supplementary pump chamber the valve mechanism of which is timed to discharge water while the main pump chamber is filling with water. The valve mechanism of the main pump chamber 1 is independent of any condition existing in the supplementary pump chamber 2 and is dependent solely upon the water levels in the main pump chamber 1 so that the main pump chamber 1 is completely filled with water at each operation regardless of the time required by the existing conditions to discharge the water from the main pump chamber 1.

What is claimed is:

1. In a pneumatic pump, the combination with a main pump chamber of a supplementary pump chamber, each of said pump chambers being provided with water inlet and outlet valves and air inlet and air exhaust valves, two fluid pressure motors differing in power and responsive to conditions existing in the main pump chamber to actuate the air inlet and air exhaust valves for both pump chambers, and means to control the said fluid pressure motors to cause the actuation of the air inlet and air exhaust valves when the water in the main pump chamber reaches predetermined levels.

2. In a pneumatic pump, the combination with a main pump chamber of a supplementary pump chamber, each of said pump chambers being provided with water inlet and outlet valves and air inlet and air exhaust valves, the main pump chamber being provided with an air exhaust port of such a size that the air exhaust valve will be held closed by the difference between the pressures on opposite sides thereof while water is being forced from the main pump chamber by air under pressure, a fluid pressure motor communicating with the main pump chamber to keep the air inlet valve closed and the air exhaust valve open for the supplementary pump chamber while the air inlet valve for the main pump chamber is open, a fluid pressure motor for opening the air exhaust valve of the main pump chamber and closing the air exhaust valve for the supplementary pump chamber, and means responsive to a predetermined low water level in the main pump chamber for causing said last mentioned fluid pressure motor to open the air exhaust valve for the main pump chamber and close the air exhaust valve for the supplementary pump chamber.

3. In a pneumatic pump, the combination with a main pump chamber of a supplementary pump chamber, each of said pump chambers being provided with water inlet

and outlet valves and air inlet and air exhaust valves, the main pump chamber being provided with an air exhaust port of such a size that the air exhaust valve will be held closed by the difference between the pressures on opposite sides thereof when air under pressure is contained in the main pump chamber, fluid pressure motors adapted to open the air exhaust valves by the pressure of the air in the main pump chamber, and means to close the air exhaust valve for the supplementary pump chamber when the air exhaust valve for the main pump chamber is opened by its fluid pressure motor.

4. In a pneumatic pump, the combination with a main pump chamber provided with water controlled valve mechanism for permitting it to fill with water and to discharge water therefrom by compressed air in accordance with predetermined variations of the water levels in said pump chamber, of a supplementary pump chamber provided with water inlet and outlet valves and compressed air inlet and outlet valves, the said compressed air valves being operated independently of variations of water level in the supplementary pump chamber by mechanism actuated by compressed air in the main pump chamber.

5. In a pneumatic pump, the combination with a main pump chamber of a supplementary pump chamber, each of said pump chambers being provided with water inlet and outlet valves and air inlet and air exhaust valves, the main pump chamber being provided with an air exhaust port of such a size that the air exhaust valve will be held closed by the difference between the pressures in the pump chamber and outside thereof, means to close the air exhaust valve and open the air inlet valve as water fills the main pump chamber to a predetermined level, a fluid pressure motor for opening said air exhaust valve, means for admitting fluid under pressure to said fluid pressure motor when the water in the main pump chamber has been lowered to a predetermined level, a second fluid pressure motor in communication with the main pump chamber for opening the air exhaust valve and closing the air inlet valve for the supplementary pump chamber, and means for closing the air exhaust valve and opening the air inlet valve for the supplementary pump chamber when the air exhaust valve for the main pump chamber is opened by said first mentioned fluid pressure motor.

In witness whereof I hereto affix my signature.

HOMER S. ROGERS.
